UNITED STATES PATENT OFFICE.

EDWARD E. HOLT, OF CHICAGO, ILLINOIS, ASSIGNOR TO HOLT AUTO DEVICES COMPANY, OF CHICAGO, ILLINOIS, A CORPORATION OF ILLINOIS.

VALVE-CAP.

1,329,182.

Specification of Letters Patent. Patented Jan. 27, 1920.

Application filed March 4, 1918. Serial No. 220,152.

To all whom it may concern:

Be it known that I, EDWARD E. HOLT, a citizen of the United States, residing at Chicago, Cook county, Illinois, have invented certain new and useful Improvements in Valve-Caps, of which the following is a specification.

The present invention has to do with improvements in valve caps for use in connection with the air valves of pneumatic tires and the like. The valve stem usually projects up through the wheel felly to the inside of the felly and it is customary to provide a suitable form of cap for closing off and protecting the end portion of the valve, so as to keep out dirt, dust, and the like. A very familiar form of valve stem at the present time found on the market is one in which the member is threaded and in which 15 the stem is cut away at each side and flattened so that it cannot rotate within the hole through which it passes through the felly. At the present time it is the general practice to so construct the valve caps that 20 they are inserted and removed by threading them onto and off from the valve stem. This means that the cap has to be threaded all the way down along the length of the stem, and it means furthermore that the 25 threading and unthreading operations will very often have to be accomplished on dirty or dusty threads.

Unless the valve cap be securely threaded onto the stem, it is liable to become unthreaded, owing to the jarring and jolting of the wheel during service. Frequently, valve caps are thus lost before the vehicle has proceeded more than a few hundred feet.

One of the objects of the present invention is to provide a valve cap of such construction that it can be slipped down directly over the threads of the stem to the desired point, and then be caused to engage 45 with said threads so as to lock the valve cap in such position. In this connection, another object is to so construct the valve cap that it can be readily removed by a similar operation, thus making it possible to either 50 attach or detach the valve cap almost instantaneously and without having to go through the laborious process of threading and unthreading.

Another object of the invention is to so

construct the valve cap that when it has once been attached to the stem, it cannot be unthreaded, thus making it impossible for the cap to become loosened or lost by reason of the jolting or jarring of the vehicle wheel. In this connection another feature 60 of the invention has reference to the provision of a construction such that advantage must be taken of the presence of the flat surfaces ordinarily to be found in the valve stems now on the market. This will 65 make it possible to use the valve cap of the present invention in conjunction with valve stems of well known construction.

Another object of the invention is to provide a very simple construction of valve 70 cap and one which can be manufactured at a very low cost and assembled in a very easy manner.

Other objects and uses of the invention will appear from a detailed description of 75 the same, which consists in the features of construction and combinations of parts hereinafter described and claimed.

In the drawing:

Figure 1 shows a vertical section through 80 a valve cap embodying the features of the present invention, the same being fully applied to a valve stem of the pipe previously mentioned;

Fig. 2 shows a view corresponding to 85 Fig. 1, with exception that the sleeve has been raised so as to disengage the threaded blocks from the threads of the stem in order to permit either insertion or removal of the cap;

Fig. 3 shows a section taken on the line 3-3 of Fig. 1, looking in the direction of the arrows, Fig. 3 being on an enlarged scale;

Fig. 4 shows a fragmentary longitudinal 95 section through the lower portion of the sleeve, being taken on the line 4-4 of Fig. 5, looking in the direction of the arrows; and

Fig. 5 shows a section taken on the line 100 5-5 of Fig. 4, looking in the direction of the arrows.

Referring to the several figures, the wheel felly is shown in fragmentary section by the numeral 6. The valve stem 7 projects 105 up through the wheel felly and receives the cap on its protruding portion. This valve stem is shown as being threaded and also as

being provided with the flattened surfaces 8 and 9.

In constructing the cap shown in the drawings, a sleeve 10 is provided of size 5 suitable to slip down over the protruding portion of the valve stem. This sleeve is provided at a suitable point with a pair of flattened surfaces or portions 11 and 12, corresponding to the flattened surfaces of 10 the valve stem. Consequently, when the sleeve is set down over the valve stem, it is locked against rotation. Adjacent to the flattened portions of the sleeve a number of openings are provided for the accommodation 15 of screw threaded segments or the like, whose function is to engage with the threads of the valve stem in order to lock the cap in position thereon. In the particular arrangement illustrated, I have shown four 20 of these openings, the same being designated 13, 14, 15 and 16.

A threaded split collar comprising the portions 17 and 18 surrounds the sleeve 10 at a point adjacent to the flattened portions 25 11 and 12. This split collar has the segmental tooth extensions 19, 20, 21 and 22, which are adapted to project through the openings 13, 14, 15 and 16, when the sections of the split collar are forced together 30 to thereby cause said threaded segments to engage with the threads on the valve stem.

Slidably mounted on the lower portion of the sleeve 10 is a cam sleeve 23, the upper portion 24 of which is of size appropriate to 35 slide easily on the body of the sleeve 10, and the lower portion 25 of which is enlarged to a size sufficient to accommodate the sections 17 and 18 of the split collar when said sections are opened apart a sufficient 40 distance to completely disengage their teeth from the teeth of the valve stem. The peripheral surface of the sections of the split collar is tapered upwardly, as is well shown in Figs. 1 and 2. The central portion 26 of the sleeve 23 is similarly tapered, so that when said sleeve 23 is forced downwardly, it will clamp or wedge the threaded sections against the valve stem.

A spring 27 tends to force the sleeve 23 50 down at all times, so as to thereby automatically wedge the threaded sections against the valve stem. The upper end of the spring 27 bears against a suitable abutment. In the particular arrangement illustrated 55 this abutment is provided by an inclosing cap 28 which is rigidly connected to the sleeve 10 and has an enlargement to accommodate the spring and provide the shoulder 29.

With the parts as thus far constituted, 60 the wedge blocks will be automatically thrust into engagement with the screw threads by the influence of the spring. In order to disengage these parts I have provided the sliding sleeve 30, the upper end

of which slides easily on the lower portion of the sleeve 28. The lower end of the sleeve 30 is flanged inwardly, as at 31, and the lower portion of the sleeve 23 bears against said flange. Therefore, by sliding 70 the sleeve 30 upwardly with respect to the sleeve 28 the sleeve 23 will also be raised against the influence of the spring to thereby permit disengagement of the threaded segments from the valve stem. Thereupon, the 75 cap may be slid either on or off without difficulty.

In order to limit the downward movement of the sliding sleeve 30 under the influence of the spring, care being taken that 80 there shall be a sufficient movement to insure proper engagement of the split collar with the threads of the valve stem, I have provided an outwardly turned flange 32 on the lower end of the sleeve 10. This flange 85 32 may also be availed of for the purpose of securing a perfectly dust-tight connection between the valve cap and the wheel felly, in order to thereby insure a dust-tight closure of all portions of the cap itself. I have, 90 therefore, shown a double washer 33, as encircling the flange 32. One portion of this washer is compressed between the flanges 31 and 32, and the other portion of the washer bears against the surface of the 95 wheel felly.

It will be understood that while I have herein shown and described a split collar having threads suitable to engage with the threads on the valve stem in order to lock 100 the cap to the valve stem, still the arrangement is not limited to the use of threads for this purpose, inasmuch as any other suitable form of connection might be adopted. Furthermore, while I have herein 105 shown and described the valve cap as being applied to a particular form of valve stem, it will also be understood that I do not limit its use to this form of valve stem, nor to any other form of valve stem.

I claim:

1. In a device of the class described, the combination with a corrugated valve stem having a longitudinally extending flattened surface, of a cylindrical member slidably 115 mounted on the valve stem and having a flattened portion adapted to engage said surface, there being a plurality of openings in said cylindrical member, a split collar comprising sections encircling the cylindrical member and having a plurality of corrugation engaging extensions adapted to pass through said openings and engage the corrugations of the valve stem, a cam sleeve 120 slidably mounted on the cylindrical member and adapted, when advanced, to force the sections of the split collar toward each other, a spring for advancing the cam sleeve, and a cylindrical closure surrounding the cam sleeve and spring and in en- 125 130

gagement with the cam sleeve for the purpose of retracting the same against the force of the spring.

2. In a device of the class described, the combination with a valve stem having a corrugated surface and a longitudinally extending flattened surface, of a cylindrical member slidably mounted on the valve stem and having a flattened portion for engagement with the flattened surface of the valve stem, a split collar comprising sections co-operatively mounted with respect to the

cylindrical member and having corrugation engaging portions adapted to engage the corrugations of the valve stem when the sections of the split collar are forced together, a cam sleeve slidably mounted with respect to the cylindrical member and adapted to engage the sections of the split collar for the purpose of forcing said sections together when the cam sleeve is advanced along the cylindrical member, and a spring for securing such advancement.

EDWARD E. HOLT.
